2 Sheets-Sheet 2

Fig. 3.

UNITED STATES PATENT OFFICE.

ARTHUR E. SPINASSE, OF MOUNT VERNON, OHIO.

GLASS-DRAWING APPARATUS.

Application filed September 9, 1926. Serial No. 134,444.

The present invention relates to improvements in glass drawing apparatus and an object of the invention is to protect the glass bath and any apparatus therein from falling fragments of glass, which have been set or partially set in the sheet of glass being drawn.

This sheet of glass passes up out of the furnace through a leer and the margin portions of the sheet frequently break off and fall down into the bath of molten glass and upon parts of the apparatus, doing injury to these parts and resulting in the drawing of imperfect glass.

15 The purpose of the invention is to interpose a barrier to the entrance of such detached particles whereby the glass bath at the drawing zone will be kept free of the particles and in condition to draw uniform 20 and perfect glass.

With the foregoing and other objects in view, the invention will be more fully described hereinafter, and will be more particularly pointed out in the claims appended hereto.

25 In the drawings, wherein like symbols refer to like or corresponding parts throughout the several views.

Figure 1 is a vertical section through portions of a glass furnace and leer casing showing the improved device.

Figure 2 is a vertical section taken on the line 2—2 in Figure 1.

Figure 3 is a section taken on the line 35 3—3 also in Figure 1, and

Figure 4 is a fragmentary section on an enlarged scale through the improved attachment.

Referring more particularly to the drawings, 5 designates the furnace roof and 6 the opening therein through which the sheet of glass, designated at 7 is drawn upwardly from the bath of glass 8 in the furnace. This sheet is, according to some methods, 40 drawn from the free or natural surface level of the glass bath, and according to other methods, through a slotted float.

The sheet 7 is received between the two sets of drawing rolls 9, 10 and 11, 12 which 50 shift the sheet upwardly in the act of drawing the same. The rollers are already mounted on appropriate journals fitted in appropriate bearings in the walls of the leer casing 13. The journals of the rolls 9 and 55 11 are provided with the beveled gear wheels 14 and 15 which are disposed respectively in

mesh with complementary beveled pinions 16 and 17 on a common shaft 18, which is driven from any appropriate source of power. The opposite drawing rolls 10 and 12 have their trunnions supported in the depending arms 19 of bell crank levers which are fulcrumed at 20 upon the leer casing and have their companion arms 21 provided with the sliding weights 22 equipped with the set screws 23, by which the weights may be adjusted along the arms 21. The weights tend to rotate the bell crank levers about the fulcrum point 20 with the result that the attached rolls are urged against the drawn sheet 7 and enough friction is secured to cause the drawing upwardly of the sheet by reason of the opposite driven roll.

Inasmuch as there is a tendency for the margin portions or edges of the sheet to draw thick or bead like, the drawing rolls are reduced or tapered at their ends, as indicated at 24 in Figure 1; otherwise the thickened edge portions would prevent the intermediate parts of the rolls from securing good contact with the body of the sheet and to this extent would interfere with positive drawing of the sheet.

It is found, however, that these tapered roll ends leave gaps between the rolls at the thickened edge portions of the sheet through which particles of the glass which break off from the edges of the sheet are enabled to fall into the glass bath 8 in the furnace to the injury of the glass being drawn. This falling glass oftentimes falls upon the refractory floats placed in the glass and these floats are broken or chipped, or otherwise injured particularly along the walls through which the sheet is drawn, so that the sheet itself is improperly drawn and checks, cracks and other blemishes occur.

According to the invention rolls 25 and 26 are provided at a point to catch and divert 100 the falling particles of glass into the catch pans 27 and 28 provided to receive same upon the furnace roof 5 adjacent the furnace opening 6. The rolls 25 and 26 are both urged yieldably against the glass sheet 7 and to this end such rolls may be carried by the depending arms 27 of the bell crank levers fulcrumed at 28 upon the leer wall or other support and having the companion angularly projecting arms 29 provided with the adjustable weights 30 by which the pressure exerted by the rolls against the sheet

and against one another through the sheet may be regulated. These rolls 25 and 26 preferably extend the full width of the sheet and preferably are longer than the sheet is 5 wide and longer than the opening 6 in the furnace roof, so as to adequately protect the drawing zone from the falling particles.

Due to the rounded peripheral surfaces on the rolls 25 and 26 the falling glass particles 10 will be diverted away from the sheet and into the catch pans 27 and 28.

As shown in Figure 3, the rolls 25 and 26 may be carried directly upon the lower ends of the swinging arms 31 and 32 pivoted upon 15 a common pivot pin or hanger 33 upon the leer wall 13 or other support.

The arms 31 and 32 will diverge downwardly as the pivot or fulcrum point 33 is arranged axially in substantially the same 20 plane with the drawn sheet 7. The result is that the rollers 25 and 26 by their own weights, will exert a yielding pressure in opposite directions upon opposite surfaces of the glass sheet.

25 In Figure 4 a preferred construction of the rollers 25 and 26 is shown in which these rollers are indicated to be constructed of a solid body of wood, metal or other material 34 mounted upon the square or other shafts 30 35 and having an outer covering or shell 36 of some soft yielding or resilient material, such as semi-soft asbestos, which is also refractory. Such yielding surfaces enable the rolls to press firmly upon the sheet without 40 producing lines or blemishes therein, and at the same time permitting the rolled surfaces to conform to the varying irregularities in the drawn sheet on both sides of the sheet, whereby no gaps will be left for the passage 45 of falling glass particles.

The glass catching rolls 25 and 26 may be placed at any appropriate point but preferably at the point where the glass becomes set. For instance these rolls 25 and 26 may be 45 placed above the drawing rolls or between the pairs of drawing rolls if desired.

It is obvious that various changes and modifications may be made in the details of construction and design of the above specifically described embodiment of this invention 50 without departing from the spirit thereof,

such changes and modifications being restricted only by the scope of the following claims.

What is claimed is:—

55 1. In glass drawing apparatus, drawing means for drawing and preserving the alignment of the sheet, and auxiliary rolls in addition to the drawing means yieldably pressed against opposite sides of the sheet 60 and positioned to divert falling particles of the glass sheet.

2. In glass drawing apparatus, drawing rolls for drawing the glass sheet, and auxiliary non-driven rolls in yieldable contact 65 with the glass sheet including the border portions thereof and rotated by the moving sheet.

70 3. In glass drawing apparatus, rigidly-mounted positively-driven drawing rolls, yieldably-mounted drawing rolls opposite said rigidly-mounted rolls for forcing the glass sheet against said rigidly-mounted rolls, and auxiliary rolls yieldably-mounted at opposite sides of the sheet to press upon 75 the sheet and be moved thereby to divert falling glass.

75 4. In glass drawing apparatus, a container for a bath of molten glass, drawing means thereabove for drawing glass sheets from the 80 bath, and rolls independent of said drawing means and between the drawing means and said bath for yieldably pressing against opposite sides of the glass sheet.

85 5. In glass drawing apparatus, a container for a bath of molten glass, drawing rolls in contact only with the intermediate portion of the sheet between the border portions thereof, and independent rolls in yielding contact with the border portions of the sheet 90 above the bath.

95 6. In apparatus for drawing sheet glass with border portions of greater thickness than the intermediate portion of the sheet, a container for a bath of molten glass, drawing rolls in contact only with the intermediate portion of the sheet between said border portions of greater thickness, and independent rolls positioned to contact with said sheet border portions of greater thickness.

In testimony whereof I affix my signature.
ARTHUR E. SPINASSE.
